UNITED STATES PATENT OFFICE.

JAMES H. GRAY, OF NEW YORK, N. Y.

ELECTRIC FURNACE.

1,113,778.

Specification of Letters Patent. Patented Oct. 13, 1914.

Application filed August 21, 1913. Serial No. 785,873.

To all whom it may concern:

Be it known that I, JAMES H. GRAY, a citizen of the United States, residing in the city, county, and State of New York, have 5 invented certain new and useful Improvements in Electric Furnaces, of which the following is a specification.

This invention aims to provide a certain improved electric furnace of the Heroult or 10 arc type designed for use in melting and refining metals and especially in the steel industry.

The main objects of the invention are to provide a furnace of large capacity, well 15 distributed and uniform heat and economical circuits.

The accompanying drawings illustrate 20 embodiments of the invention.

Figures 1, 2 and 3 are horizontal sections of three different types of furnace: Fig. 4 is a vertical section of the furnace shown in Fig. 3; showing the electrodes in perspective. Fig. 5 is a horizontal section of a furnace of larger capacity.

25 Referring to the embodiments of the invention illustrated, the furnace is provided with a hearth A for receiving the molten metal B above which are the electrodes C with their lower ends only slightly above 30 the surface so as to form arcs to the metal, the upper ends of the electrodes passing through the roof D. The electrodes are adjustable in any usual or suitable way to lower them as their lower ends are consumed. The furnace is of a general oblong 35 shape having side walls E and having its ends tapered and rounded as at F in Figs. 1 and 5 or squared as at F', Figs. 2 and 3, with rounded corners.

40 The electrodes are distributed as uniformly as possible over the superficial area of the bath and with uniform distances between the electrodes of each group. Subject to these considerations the location of 45 the electrodes must depend upon the shape of the furnace. The electrodes are also arranged in groups, each group being electrically connected to one transformer or other source of current. Preferably for 50 smaller furnaces, Figs. 1, 2 and 3, there are two groups of three electrodes each, while for larger furnaces, as in Fig. 5, there are two end groups of three each and an intermediate group or groups having four electrodes or any other number of electrodes.

depending on the size of the furnace. The three electrodes C', C² and C³ of each of the three-electrode groups are connected to the respective terminals of a three-phase secondary circuit G of a transformer, whose primary circuit H is connected to the mains J of a three-phase system operated by a generator K. Any usual or suitable regulators for controlling the current and the positions of the electrodes may be used. The 60 circuit is arranged in delta, that is with the coils L, M and N arranged in a continuous circuit and each of the conductors O, P and Q connected at a point between two of the coils, so that the current will pass successively down through each one of the electrodes and up through the other two.

65 In the arrangement shown in Fig. 1 one of the groups of three electrodes is at one end of the furnace and the other at the opposite 70 end. In the arrangement of Fig. 3 one of the electrodes of each group is over the middle portion of the bath so that to this extent the areas covered by the two groups overlap. In Fig. 2 there is a complete overlapping, each group having one electrode at 75 each end of the furnace and one at the middle portion thereof. The overlapping of the groups distributes the effects of the two groups more uniformly when there is any 80 difference between the working of the two groups. This is important because of the 85 localization of the heating effect on the metal at and adjacent to the arcs. The complete overlapping as shown in Fig. 2 has the 90 further advantage of permitting a fairly 95 good operation of the furnace with only one group of electrodes if this should be necessary or desired for any reason.

Fig. 5 shows a furnace of approximately 100 the same shape in horizontal section as Fig. 1 and with electrodes in groups of three at the opposite ends the same as Fig. 1. The furnace of Fig. 5, however, is designed for a larger capacity and is, therefore, made of 105 extra length and the space between the end groups of electrodes is covered by an additional group of four electrodes R', R², R³, R⁴ equally spaced from each other and from the adjacent electrodes of the end groups. This central group of electrodes is served by a two-phase current which is transformed through a Scott's connection from a three-phase current; such a connection being indicated diagrammatically at S, T, T' 110

and S', T'. The current is alternating, one phase passing alternately down through R' and up through R² and in the opposite direction, and the other phase passing similarly through R³ and R⁴.

5 The tap hole U of the furnaces is usually arranged on the side as shown. In pouring the metal from furnaces of substantially rectangular shape, and especially in 10 smaller furnaces where the banks of the hearth are more nearly vertical there is a tendency of the slag to stick near the corners. This tendency is obviated or materially reduced by making the furnace with 15 tapering ends as shown in Figs. 1 and 5.

What I claim is:—

1. An electric arc furnace for the melting and refining of metals comprising a hearth for carrying the molten metal, and electrodes above the metal with their lower ends adjacent to the surface thereof to form an arc between each electrode and the metal, said electrodes comprising a plurality of groups of three each, the three electrodes of 20 each group being connected to the respective terminals of a three-phase circuit arranged in delta so that the current passes successively down through each electrode and up through the other two electrodes of 25 the group.

2. An electric arc furnace for the melting and refining of metals comprising a hearth for carrying the molten metal, and electrodes above the metal with their lower ends 30 adjacent to the surface thereof to form an arc between each electrode and the metal, said electrodes comprising a plurality of groups of three each, the three electrodes of each group being connected to the respective 35 terminals of a three-phase circuit arranged in delta so that the current passes successively down through each electrode and up through the other two electrodes of 40 the group, the area covered by one group 45 overlapping that covered by another group so as to distribute the effect as uniformly as possible.

3. An electric arc furnace for the melting and refining of metals comprising an ob- 50 long hearth for carrying the molten metal, and electrodes above the metal with their lower ends adjacent to the surface thereof to form an arc between each electrode and the metal, said electrodes being six in number and being arranged in two groups of 55 three each, the three electrodes of each group being connected to the respective terminals of a three-phase circuit arranged in delta so that the current passes successively 60 down through each electrode and up through the other two electrodes of the group.

4. An electric arc furnace for the melting and refining of metals comprising an ob- 65 long hearth for carrying the molten metal, and electrodes above the metal with their

lower ends adjacent to the surface thereof to form an arc between each electrode and the metal, said electrodes being six in number and being arranged in two groups of three each, the three electrodes of each group being connected to the respective terminals of a three-phase circuit arranged in delta so that the current passes successively down through each electrode and up through the other two electrodes of the group, the area of one group overlapping that of the other so as to effect a uniform distribution and so as to permit the operation of the furnace with only one group, if desired.

5. An electric arc furnace for the melting and refining of metals comprising a hearth for carrying molten metal and electrodes above the metal with their lower ends adjacent to the surface thereof to form an arc between each electrode and the metal, said 70 hearth having tapered ends and said electrodes comprising groups of three each, one group at each end of the hearth.

6. An electric arc furnace for the melting and refining of metals comprising a hearth for carrying molten metal and electrodes above the metal with their lower ends adjacent to the surface thereof to form an arc between each electrode and the metal, said 75 hearth being oblong in shape and said electrodes comprising a plurality of independent groups at opposite ends of the hearth and an additional group of electrodes between said end groups.

7. An electric arc furnace for the melting and refining of metals comprising a hearth for carrying molten metal and electrodes above the metal with their lower ends adjacent to the surface thereof to form an arc between each electrode and the metal, said 80 hearth being oblong in shape and said electrodes comprising two independent groups of three electrodes each at the respective ends of the hearth and an intermediate group of four electrodes spaced equally 85 from each other and from the adjacent electrodes of the end groups.

8. An electric arc furnace for the melting and refining of metals comprising a hearth for carrying molten metal and electrodes above the metal with their lower ends adjacent to the surface thereof to form an arc between each electrode and the metal, said 90 hearth being oblong in shape and said electrodes comprising two independent groups of three electrodes each at the respective ends of the hearth and an intermediate group of four electrodes, the groups of three electrodes being served with a three phase current and the group of four electrodes 95 being served with a two phase current obtained by transformation from a three phase circuit through a Scott's connection.

9. An electric arc furnace for the melting and refining of metals comprising a hearth 100

for carrying molten metal and electrodes above the metal with their lower ends adjacent to the surface thereof to form an arc between each electrode and the metal, said hearth being of elongated shape in plan and having its ends tapered and its tap hole at one of the sides.

In witness whereof, I have hereunto signed my name in the presence of two subscribing witnesses.

JAMES H. GRAY.
